FOUNTAIN PEN AND INK ERADICATOR

Stanley Lehman, Madison, Wis.

Application October 28, 1943, Serial No. 507,999

2 Claims. (Cl. 120—37)

My invention relates to the eradication of ink, and has among its objects and advantages the provision of an improved fountain pen and ink eradicator.

In the accompanying drawing:

Figure 1 is a view of a pen embodying my invention.

Figure 2 is a longitudinal sectional view of the pen portion.

Figure 3 is a longitudinal sectional view of the ink eradicator section.

In the embodiment of the invention selected for illustration, I make use of a barrel 10 comprising a pen barrel section 12 and an eradicator barrel section 14. A conventional fountain pen unit 16 is connected with one end of the barrel section 12 and includes the usual ink sac 18 which may be collapsed through the medium of a pivoted lever 20 arranged to bear on a collapsing spring 22. The structure so far described is old and well known in the art. The unit 16 is housed in a removable cap 24 in the usual manner.

The eradicator section 14 includes an externally threaded neck 26 for threaded connection with the internally threaded end 28 of the section 12. Inside the section 14 is arranged a collapsible sac 30 for the ink eradicator fluid. This sac is carried by a tubular body 32 having a threaded connection at 34 with the end flange 36 of the section 14.

The body 32 has an annular shoulder 38 which engages the flange 36, but the body is removable from the flange with the sac 30. A glass applicator tip 40 is secured in a bore 42 in the body 32 and concentrically of the body bore 44. A small opening 46 is provided in the rounded outer end of the tip 40.

A cap 48 is threadedly connected at 50 with the section 14, and this cap includes a compression spring 52 engaging a cup 54 in which is secured an annular blotter body 56 into which the tip 40 is partly projected. A sealing gasket or plate 58 is pressed into the blotter body 56, and constitutes a closure for the opening 46.

A spring 60 is provided for collapsing the sac

30 which spring is associated with a pressure lever 62 corresponding to the lever 20.

In operation, the sacs 18 and 30 are independent so that either may be filled without interfering with the other. The tip 40 is rendered available by merely unscrewing the cap 48 to permit the ink eradicator to be applied from the tip.

Without further elaboration, the foregoing will so fully explain my invention, that others may, by applying current knowledge, readily adapt the same for use under various conditions of service.

I claim:

1. An ink eradicator reservoir and applicator 15 for use with fountain pens, comprising a hollow body with open ends, one end adapted for attachment to a fountain pen casing and a threaded body carrying a collapsible eradicator sac engaged with the other end of the hollow body, said

20 threaded body having a bore communicating with the sac, a hollow applicator tip with an outlet opening carried by the body and communicating with the bore, a cap on the hollow body, a cup in the cap, a blotter body in the cup, and a spring 25 between the cup and the end of the cap to press the blotter against the opening in the applicator tip to seal the same.

2. An ink eradicator reservoir and applicator 30 for use with fountain pens, comprising an elongated tubular body with open exteriorly threaded ends, one end adapted for attachment to a fountain pen casing forming a closure, a threaded hollow body carrying a collapsible eradicator sac, and engaged with the other end of the elongated tubular body, an elongated hollow cylindrical applicator tip with an outlet opening there-

35 in carried by the body and communicating therethrough with the sac, a cap on the tubular body, a cup in the cap, a blotter body, a gasket holding the blotter body in the cup, and a compression spring between the cup and the end of the cap to press the blotter against the opening in the applicator tip to seal the same.
